UNITED STATES PATENT OFFICE.

WILLIAM W. CONNER, OF NILES, OHIO.

CORK-EXTRACTOR.

No. 893,055.

Specification of Letters Patent.

Patented July 14, 1908.

Application filed January 23, 1908. Serial No. 412,332.

To all whom it may concern:

Be it known that I, WILLIAM W. CONNER, a citizen of the United States, residing at Niles, in the county of Trumbull and State of Ohio, have invented a new and useful Cork-Extractor, of which the following is a specification.

This invention relates to cork extractors and has for its object to provide a comparatively simple and inexpensive device of this character by means of which a cork or other closure may be withdrawn from the neck or interior of a bottle or other containing vessel with ease and facility.

15 A further object of the invention is to provide a cork extractor including a plurality of spring arms having terminal gripping spurs or fingers adapted to engage the cork or stopper to be extracted, said arms being 20 movable to closed position by an operating member slidably mounted on the shank of the tool.

25 A still further object of the invention is generally to improve this class of devices so as to increase their utility, durability and efficiency as well as to reduce the cost of manufacture.

30 Further objects and advantages will appear in the following description, it being understood that various changes in form, proportions and minor details of construction may be resorted to within the scope of the appended claims.

35 In the accompanying drawings forming a part of this specification: Figure 1 is a side elevation of a cork extractor constructed in accordance with my invention showing the spring arms in extended or inoperative position. Fig. 2 is a sectional view showing the 40 arms moved to operative position. Fig. 3 is a transverse sectional view taken on the line 2—2 of Fig. 1. Fig. 4 is a detail side elevation of the lower ends of the spring arms showing the same in assembled position for 45 transportation or shipment. Fig. 5 is a side elevation illustrating a modified form of the invention.

50 Similar numerals of reference indicate corresponding parts in all of the figures of the drawings.

55 The improved cork extractor forming the subject matter of the present invention is preferably formed of a plurality of strands of wire, one of said strands having an intermediate portion thereof bent upon itself to form a finger loop or handle 5, the wire being

thence intertwined to produce a shank or body portion 6 terminating in a pair of diverging spring arms 7. The intermediate portion of the other strand of wire is coiled 60 around the shank 6 with one end thereof wrapped or coiled around the loop 5 and with the opposite end extended laterally to form a third spring arm 8. The terminal portions of the spring arms 7 and 8 are bent 65 inwardly to form gripping spurs or fingers 9 adapted to bite into the cork or stopper to be extracted.

70 Slidably mounted on the shank 6 is an operating member comprising a longitudinally disposed rod 10 having its opposite ends bent to form terminal guide rings 11 and 12 which embrace the shank 6 and serve to force the spurs of the arms 7 and 8 into engagement with the cork or stopper when the operating 75 member is moved to lowered position, as best shown in Fig. 2 of the drawings.

76 The upper guide ring 11 is provided with a lateral off set portion 13 in which is pivotally mounted an extension rod 14, one end of the extension rod being provided with an eye 15 for engagement with the off set portion 13, while the opposite end thereof is bent to form a finger loop 16.

80 The extension rod 14 is employed when the extractor is used for withdrawing stoppers from the interior of bottles or jars having contracted necks and relatively deep body portions, or wherever it is found difficult to insert the finger in the neck of the 85 bottle to operate the member 10.

86 Attention is here called to the fact that the lower ring 12 by engagement with the spurs or fingers 9 serves to limit the downward movement of the operating member so 90 as to prevent accidental displacement of the same during transportation or shipment.

95 In operation the shank of the tool is introduced through the neck of the bottle and said tool lowered into the interior of the latter until the spurs 9 are positioned over the cork to be extracted after which a downward pressure is exerted on the finger loop of the extension rod 14 which operates the member 10 to contract the arms 8 and thus force the 100 spurs 9 into engagement with the cork so that by exerting a slight upward pull on the finger loop or handle 5 the cork may be readily withdrawn through the neck of the bottle.

105 By having the extension rod pivotally connected with the upper ring of the operating

member, said extension rod may be folded laterally against the shank so as to occupy very little space when it is desired to compactly assemble several of said implements 5 in a box for transportation or shipment.

When it is desired to extract the stopper from the neck of a bottle the spurs 9 are positioned over the projecting end of the stopper and an upward pull exerted on the finger 10 loop 5, in the manner before stated.

In Fig. 5 of the drawings there is illustrated a modified form of the invention in which the extension rod 14 is dispensed with and the shank 6' made relatively short, the 15 spring arms 7' being approximately three times the length of the shank.

While the implement is principally designed for extracting corks it is obvious that the same may be used with equally good results for cleaning the interior of bottles, jars, 20 large chimneys and the like by inserting a strip of cotton, sponge or other soft material between the fingers of the spring arms, as will be readily understood.

From the foregoing description it will be seen that there is provided an extremely simple, inexpensive and efficient device admirably adapted for the attainment of the ends in view.

Having thus described the invention what is claimed is:

1. A cork extractor comprising a shank having one end thereof terminating in a handle and its opposite end provided with a plurality of diverging spring arms having inwardly extending gripping spurs, an operating member slidably mounted on the shank and provided with oppositely disposed guide loops, one of which is movable longitudinally of the spring arms for forcing the spurs into engagement with a cork, and an extension rod pivotally mounted on the other guide loop of the operating member.

2. A cork extractor comprising a shank 45 having one end thereof formed with a finger loop and its opposite end provided with a plurality of diverging spring arms terminating in inwardly extending gripping spurs, an operating member slidably mounted on the shank and provided with oppositely disposed 50 guide loops, one of said guide loops being movable into engagement with the spring

arms for forcing the spurs in contact with a cork, the other guide loop being provided with a lateral offset portion, and an extension 55 rod pivotally mounted on the off set portion of the loop and provided with a terminal finger piece.

3. A cork extractor comprising a body portion formed of a plurality of wire strands 60 one of which is bent upon itself to form an intermediate finger loop and thence twisted to produce a shank terminating in a pair of spring arms having laterally extending spurs, the other wire strand being coiled around the 65 shank and having one end thereof twisted around the finger loop and its opposite end extended longitudinally of the shank to form a third diverging spring arm provided with a similar spur, and an operating member 70 slidably mounted on the shank and comprising a rod having oppositely disposed guide loops for the reception of the shank, one of said guide rods being movable longitudinally of the spring arms for forcing the 75 spurs into engagement with a cork.

4. A cork extractor comprising a body portion formed of a plurality of wire strands one of which is bent upon itself to form an intermediate loop and thence twisted to produce a shank terminating in a pair of spring arms having laterally extending spurs, the other wire strand being coiled around the shank and having one end thereof twisted around the finger loop and its opposite end 80 extended longitudinally of the shank to form a third diverging spring arm provided with a similar spur, an operating member slidably mounted on the shank and comprising a rod having oppositely disposed guide loops for 85 the reception of the shank, one of said guide loops being formed with an off set portion, and an operating rod pivotally mounted on said off set portion, the other guide loop being movable longitudinally of the spring arms for 90 forcing the spurs into engagement with a cork.

In testimony that I claim the foregoing as my own, I have hereto affixed my signature in the presence of two witnesses.

WILLIAM W. CONNER.
